UNITED STATES PATENT OFFICE.

WILLIAM S. SCHROEDER, OF CHICAGO, ILLINOIS, ASSIGNEE TO CHARLES A. SCHROYER,
OF OAK PARK, ILLINOIS.

YOKE FOR DRAFT-GEAR.

1,256,267.

Specification of Letters Patent. Patented Feb. 12, 1913.

Application filed August 21, 1913. Serial No. 115,250.

To all whom it may concern:

Be it known that I, WILLIAM S. SCHROEDER, a citizen of the United States, residing in Austin, Chicago, in the county of Cook 5 and State of Illinois, have invented a new and useful Improvement in Yokes for Draft-Gears, of which the following is a specification.

This invention relates in general to yokes 10 for draft gears and has for its object broadly the provision of a yoke for a draw bar of new and improved construction and from which the draw bar may be removed from the front and without requiring the 15 removal of the yoke.

The invention has for its further object the provision of a yoke for a draft gear of greatly increased strength and of simple and economic construction.

20 A still further object of the invention is the provision of such a structure in which the draw bar when secured will engage on all four sides.

Another object of the invention is the 25 provision of a yoke for a draw bar so constructed and arranged that the draw bar itself insures against separation of the parts of the yoke.

Other objects and advantages of the invention will be apparent as it is better understood from the following description when considered in connection with the accompanying drawings illustrating a preferred embodiment thereof.

35 Referring to the drawings,

Figure 1 is a side elevation of a yoke embodying my present invention;

Fig. 2 is a top plan view of the same;

Fig. 3 is a section taken substantially on 40 the lines 3—3 of Fig. 1;

Fig. 4 is section taken substantially on the lines 4—4 of Fig. 1;

Fig. 5 is a side elevation of a somewhat modified form of my invention;

45 Fig. 6 is a top plan view of the same;

Fig. 7 is a section taken substantially on the lines 7—7 of Fig. 5; and

Fig. 8 is a section taken substantially on the lines 8—8 of Fig. 5.

50 For the purpose of illustrating my invention I have shown on the drawings two em-

bodiments of it, the first of which that shown in Figs. 1 to 4 differs only from that shown in Figs. 5 to 8 in that in the former are included certain novel features possessing peculiar advantages which are not found in the form shown in Figs. 5 to 8.

Referring more particularly to Figs. 1 to 4, it will be noted that I have shown a draw bar 11 of ordinary construction having the usual coupler 12 and butt 13. The butt 13 is provided with the usual transversely extending key aperture 14.

In this embodiment of the invention the yoke consists primarily of a head 15 and a 65 metal strap 16 which forms the two limbs and rear or tail of the yoke and which provides for the reception of the follower plates and springs (not shown). The head 15 is preferably of cast metal and is provided with relatively thick vertical side walls 17. In the inner face of each of these walls an offset slot 18 is provided lower at its entrance 19 than at its rear part 20 so that vertical shoulders 21 are provided. The 70 parts are so constructed that the ends of the key 22 positioned through the butt of the draw bar may enter into these slots and when the draw bar and butt are elevated, as will be later described, rest in these guide- 75 ways and in position to engage the shoulders 21. The head is provided with a shoulder 23 at the forward edge of the top wall 24 which may engage in front of the butt 13 at the top.

The metal strap 16 is preferably of U shape and has its extreme ends 25 bent outwardly and adapted to rest in the slots 26 provided in proper position in the top wall 24 and in the floor or bottom wall 27. Projections or studs 28 are provided to extend inwardly from the top wall and floor behind the slots. The ends of the strap are provided with apertures 29 in which these projections are adapted to seat when the 95 parts are assembled. The outwardly turned or bent ends of the strap are recessed at 31 to permit passage of the projections without unduly drawing the ends of the yoke together to bring them into position to enter 100 the slots. After positioning the ends of the strap through the slots their extremities may

be riveted down to hold the parts together. The lower limb is bent downwardly at 32 and a transversely sliding member 33 in engagement with this limb and with the floor 5 of the head is placed under the draw bar after the key ends have been inserted in the ends of the guide-ways. Suitable apertures 30 are provided in the lower parts of the side walls to permit the sliding member to 10 be inserted. This sliding member elevates the draw bar so that the ends of the key are behind the shoulders 21 and so that the upper forward edge or face of the butt is behind the shoulder at the forward edge of 15 the top of the head. The transversely sliding member 33 is L shaped in cross section, one part of the L resting in full face contact in part with the floor and in part with the forward end of the lower limb of the strap, 20 and the other part of the L is disposed in front of the lower forward shoulder of the draw bar so that when this sliding member is in place the draw bar butt has a four-sided engagement with the head. The trans- 25 versely sliding member lifts the butt into proximity with the forward end of the upper limb of the strap and thus insures against its displacement. A cotter pin or key is used to hold this member in place. It 30 will be understood that the parts need not be riveted and that the butt may be used in this manner to hold the limbs in place, the top limb by engagement with the top of the butt, and the lower limb by engagement with 35 the transversely sliding member.

In constructing the yoke of the strap and cast head it is possible to use wrought metal which may be tougher than the cast metal of the head in the thinner parts of the structure and a peculiarly strong structure is thereby attained.

It will be understood, however, that the yoke and limbs may be constructed of integral metal and Figs. 5 to 8 disclose an embodiment in which such is the arrangement. The structure shown in these figures does not differ materially in other respects from that shown in Figs. 1 to 4. Viewing Figs. 5 to 8 it will be noted that the draw bar 51 is provided with a butt 52 in all respects like the butt 13 of the draw bar 11 and this butt rests in a head 53 of the yoke which is identical in construction with the head 15 of the yoke already described, except that no slots 45 or apertures are provided for the reception of strap ends. The limbs 54 and 55 in this form are made integral and extend rearwardly from the top and bottom walls of the head being closed in the usual fashion 50 at 56 at the rear or tail. The head 53 is provided with offset guide-ways 57 and with openings 58 near the lower edges of the side walls of the head through which openings 53 may be inserted the transversely sliding 55 member 59 identically like the transversely

sliding member 33 of the embodiment earlier described.

In both embodiments the four sided engagement of the butt and the head is present and this engagement is maintained by 70 the sliding member which has a full face contact with its support, *i. e.* the floor or bottom of the head in the embodiment of the invention shown in Figs. 5 to 8.

The sliding member in each embodiment 75 is preferably so dimensioned that when the draw bar is forced rearwardly out of the yoke head in busing the butt will slide on to the main part of the lower limb of the yoke, the upper face of the part of the sliding 80 member on which the butt normally rests being in line with the upper face of the lower limb. The key ends limit this rear movement while permitting sufficient range of action by their entrance in the parts 20 85 of the guideways.

It will be manifest from the foregoing that with either form of the invention the butt of the draw bar may be inserted in place from the front and without requiring 90 removal of the yoke. The parts are simple and of strong, sturdy construction and it will be obvious that various changes may be made in the form, construction and arrangement of the parts without departing 95 from the spirit and scope of the invention or sacrificing any of its material advantages, the forms hereinbefore described being merely preferred embodiments thereof.

I claim:

1. A yoke for a draft gear comprising a head having a slot in one of its horizontal walls, and having a stud projecting downwardly behind said slot, and a metal strap forming the limbs and rear or tail of said 105 yoke, and having an end bent to enter said slot, and having also an aperture adapted to receive said stud.

2. A yoke for a draft gear comprising a head having a slot in one of its horizontal 110 walls, and having a stud projecting downwardly behind said slot, and a metal strap forming the limbs and rear or tail of said yoke, and having an end bent to enter said slot, said bent end being cut away to permit 115 it to pass said stud.

3. A yoke for a draft gear comprising a head having slots in its upper and lower walls, a metal strap having its ends bent to enter said slots from within said head, the 120 lower limb being bent downwardly at the head, and a member slidably across the bent down portion of said limb to hold the butt of a draw bar elevated thereabove and in close proximity with the forward end of the 125 upper limb.

4. A yoke for a draft gear comprising a head having slots in its upper and lower walls, and a metal strap forming the limbs and rear or tail of the yoke and having its 130

ends bent to enter said slots, and a member sliding across the lower limb and beneath a draw bar positioned in said yoke, said member holding the draw bar with its butt in 5 close proximity with the forward end of the upper limb.

Signed in the presence of two subscribing witnesses.

WILLIAM S. SCHROEDER.
